FULL-WAVE RECTIFIER TUBE

Charles Norman Smyth, London, England, assignor, by mesne assignments, to International Standard Electric Corporation, New York, N. Y., a corporation of Delaware

Application January 20, 1945, Serial No. 573,774
In Great Britain February 7, 1944

11 Claims. (Cl. 250—27.5)

1

The present invention relates to thermionic rectifiers and rectifying circuits of the full wave type and concerns particularly but not exclusively, a valve design suitable for miniature rectifiers, or for other cases where the anode dissipation is relatively large.

A full wave rectifier comprising two diodes assembled in the same envelope is well known, and both cathodes are usually operated at the same potential; quite commonly a single cathode serves for both the diodes, two separate anodes being provided. In the conventional rectifying circuit the anodes are at high A. C. potentials in opposite phase, and the cathodes are usually at a high positive potential. It is therefore necessary to insulate the cathode heating circuit to stand up to any voltages likely to occur between the cathodes and earth, and this is done either by suitably insulating the heaters themselves from the cathodes or by supplying them from a suitably insulated source such as an insulated transformer winding, or by both methods.

Power rectifiers of this type have considerable anode dissipation, and radiating fins are often provided on the anodes inside the envelope to keep them at a reasonable temperature during operation. In cases where space is a consideration, it has been found difficult to reduce the size of these rectifiers sufficiently on account of the bulky nature of the cooling arrangements.

Half wave rectifiers have of course been made in which the anode is part of the envelope, enabling external cooling means to be applied, but as in the conventional arrangements the anode is operated at a high A. C. potential, an external anode has obvious disadvantages. The provision of two such high potential external anodes for a full wave rectifier presents considerable difficulties.

It has been found that all these troubles may be avoided, and full wave rectifiers of small dimensions may be constructed by designing the rectifier with a common anode but with separate cathodes, and by modifying the circuit arrangements so that the common anode is operated at ground potential. The common anode then preferably comprises a metal disc sealed through the envelope of the rectifier valve, to which disc may be integrally attached extension plates, or the like, close to the cathodes to form the anode surfaces which collect the electrons from the cathodes, and also possibly to screen the cathodes from one another, the arrangement being, for example, on similar lines to the disc seal anode valve described in the specification of the co-

2

pending application, Serial No. 572,410, filed January 11, 1945.

The invention accordingly provides a thermionic valve rectifier comprising an envelope, a plurality of electron emissive cathodes insulated from one another enclosed in the said envelope, and a single anode common to all the said cathodes.

The invention also provides an electrical circuit arrangement for rectifying a multi-phase alternating voltage comprising a thermionic valve rectifier having a plurality of insulated electron emissive cathodes corresponding respectively to the phases and an anode common to all the said cathodes, means for applying between each cathode and a neutral point, an alternating voltage in the phase corresponding to that cathode, and means for connecting a direct current load between the said anode and the said neutral point.

20 The invention will be described with reference to the accompanying drawings, in which—

Figs. 1 and 2 show schematic diagrams of two rectifying circuits according to the invention;

Fig. 3 shows a side view of a thermionic valve 25 rectifier according to the invention;

Fig. 4 shows a plan view of the anode disc of Fig. 3;

Figs. 5 and 6 show modifications of the valve according to Fig. 3;

Fig. 7 shows a preferred terminal arrangement 30 for the valve; and

Fig. 8 shows a valve similar to Fig. 3 provided with a metal can.

Fig. 1 shows a schematic circuit diagram of a 35 full wave rectifying arrangement according to the invention. A rectifier valve V in the form of a double diode has a single anode A and two cathodes C₁ and C₂ with corresponding insulated heaters H₁ and H₂. This valve is shown purely diagrammatically and is not necessarily arranged with the cathodes on opposite sides of the anode. A power transformer T has a primary winding P connected to a single phase source of alternating current as indicated, and a centre-tapped secondary winding S₀ having its extreme terminals connected respectively to the cathodes C₁ and C₂. Two additional secondary windings S₁ and S₂ are respectively connected to the heaters H₁ and H₂. The rectified voltage is obtained from the terminals 1 and 2 connected respectively to the anode A and to the centre tap of the winding S₀. Terminal 1 will be the negative terminal and should preferably be connected to earth, as shown, so that the anode A will be at ground potential. Suitable smoothing filters (not shown)

may be connected between the terminals 1, 2 and the load according to the usual practice.

It will be seen that in this arrangement the cathode potential can rise to a value equal to the sum of the A. C. and D. C. potentials. The cathodes must therefore be very well insulated from earth. As it is often difficult to provide insulation between the cathodes and their respective heaters which will stand up to such high voltage, each heater is preferably supplied with current from a separate transformer winding appropriately insulated. This would permit each cathode to be connected to its heater, and would also allow directly heated cathodes to be used. If, however, the heaters are satisfactorily insulated from their respective cathodes, then they could be both heated from a single transformer winding, either in series or in parallel, or from some other source not necessarily insulated from ground.

It is to be noted that means should preferably be provided to prevent direct communication of electrons from one cathode to the other. One way of doing this is to place the cathodes on opposite sides of the anode in the manner diagrammatically shown in Fig. 1. Another way is to interpose an extension of the anode between the two cathodes to act in the manner of a screen, or to enclose the cathodes in separate metal tubes or boxes connected together or attached to a common metal plate.

Still another expedient is to remove the activating material from adjacent surfaces of the two cathodes so that neither emits electrons on the side facing the other.

Exactly the same principles are applicable to a multiphase rectifier. A separate cathode is provided for each of the phases concerned and all share a common anode. Fig. 2 shows how the circuit could be arranged in the case of a three-phase rectifier. The rectifying valve V has a single anode A and three separate cathodes C₁, C₂ and C₃ with corresponding insulated heaters H₁, H₂ and H₃. Only the three secondary windings W₁, W₂ and W₃ of the three-phase transformer connected to a three-phase supply are shown, and they are arranged in star formation with the points of the star connected respectively to C₁, C₂ and C₃. The terminals 1, 2 for the rectified voltage are connected respectively to the anode A and to the common point of the three secondary windings, and terminal 1 is preferably connected to ground, as shown. The three heaters H₁, H₂ and H₃ may be connected to corresponding extra insulated secondary windings (not shown) of the three-phase transformer, or if suitably insulated they may be all supplied from a common winding or other common source.

To prevent direct transfer of electrons between the cathodes, extension plates such as are indicated at A₁ and A₂ may be attached to the anode A to screen each cathode from its neighbour. Each cathode will then supply electrons substantially only to the anode.

It will be evident that a rectifying valve for any number of phases greater than three can be arranged in a similar way. The output secondary windings corresponding to the phases will be connected to a common point which is connected to the positive output terminal, and the remaining terminals of these windings will be connected respectively to a corresponding number of cathodes provided in the valve V, the common anode of which is connected to the negative output terminal, and is preferably also connected to ground.

Fig. 3 shows a preferred form of construction for a rectifying valve having two cathodes, and suitable for use in the circuit of Fig. 1. To the upper side of a disc 11 of copper or other suitable metal is sealed a glass dome 12, and to the lower side of the disc is likewise sealed a glass cup 13 having a glass disc base 14 carrying a number of terminal pins or rods 15 sealed therethrough.

Mounted on the terminals as indicated by 10 means of the wires 16 and 17 (or in any other convenient way) is an assembly comprising two mica sheets 18 and 19 holding the two cathodes 20 and 21 having corresponding heaters (indicated by the dotted lines) fixed therein in any 15 suitable way. The cathodes and heaters are connected by suitable wires to corresponding terminals 15 as indicated.

Anode extension plates 22, 23 and 24 are soldered or spot-welded or otherwise rigidly attached to the disc 11, and are located in slots in the mica sheets 18 and 19. The view of the underside of disc 11 seen in Fig. 4 indicates how these plates appear in plan. A getter holder 25 is located inside the dome 12 (Fig. 3) and is secured to the disc 11. The valve is finally exhausted and sealed off at the tip 26.

The valve may be constructed in substantially the same way as those described in the co-pending application previously referred to. Thus the 30 disc 11 with the plates 22, 23 and 24 already attached is first sealed to the dome 12, and the getter holder 25 is inserted through the slot 27 (seen in Fig. 4) provided for the purpose in the disc, and is soldered into the small hole 28. The 35 cathode assembly is mounted in the cup 13, and the two parts are then brought together so that the anode extension plates enter the corresponding locating slots in the mica sheets 18 and 19. The seal between the cup 13 and the disc 11 is finally made. The valve may then be outgassed and exhausted and the getter fired, and afterwards it may be sealed off at the tip 26.

Fig. 5 shows in section a variation in which two 45 anode extension plates attached to the disc 11 are provided, the section being taken roughly half way between the two mica sheets 18 and 19 in Fig. 3. The two cathodes 20 and 21 are placed side-by-side between the two anode plates 29 and 30, and a screening partition 31 connected to the 50 anode plates is placed between them. The mica sheets 18 and 19 will, of course, be provided with locating slots appropriate for the modified form of the anode extension plates.

If the mutually adjacent surfaces of the cathodes 20 and 21 are not coated with emissive material, the screening partition 31 could be omitted if desired. This partition also need not be integral with the anode disc or plates, but it is desirable to connect it thereto.

60 In the arrangements described with reference to Fig. 3 or 4, the leakage path between the cathodes and the anode may be rather short, and to avoid this the anode extension plates may be shaped in reentrant form. Thus Fig. 6 shows, 65 for example, how the plates of Fig. 5 may be arranged. Fig. 6 is a side view of the assembly as it would be seen from the right hand side of Fig. 5. Owing to the form of the plates 29 and 30 they preferably constitute part of the lower assembly, and are placed in position in the mica sheets before the two parts of the valve are brought together for final sealing. The upper ends of these plates are provided with suitable tongues which enter locating slots at 32 and 33 70 in the disc 11, being soldered in place during the 75

final processing of the valve. The partition 31 could be initially attached to the disc 11 or to the plates 29 and 30 as may be most convenient, but should be long enough to screen the cathodes from one another over their whole length. Relatively wide clearance slots for the partition 31 should be left in the mica sheets 33 and 34 so as to avoid shortening the leakage path. Since, in the case of Fig. 6 the mica sheets will probably be more nearly square in shape, it may be desirable to provide four supporting wires at the corners, and two of these wires are indicated at 34 and 35.

The structure which has been described with reference to Figs. 3 to 6 is particularly suitable for miniature rectifying valves, and for such valves a standard glass disc base 14 is available, having seven pin terminals. This base is shown in plan in Fig. 7 where the seven pin terminals are marked with the same letters *a* to *g* shown in Fig. 3.

The connections of the two cathodes and their heaters should preferably be as indicated in Figs. 3 and 7. Terminal *d* is left blank, and this arrangement provides the best separation for terminals with a large potential difference between them.

According to the usual practice when disc terminals are used, the anode disc 11 will preferably be clamped or sandwiched between two relatively heavy metal rings or plates making very good thermal contact, so that very rapid transfer of heat from the anode is obtained. In this way a very small rectifying valve may be provided while at the same time dissipating a large quantity of heat. As shown in Fig. 8 the metal clamping rings or plates may be part of a metal can 36 enclosing the valve, and radiating fins 37 may be provided on the outside of the can if desired. The can may be connected to the unused pin *d* of the base, or it may be provided with a central peg and key 38 as indicated in Fig. 8 for connecting to a corresponding socket which may be connected to ground for earthing the can. If it should be desired to insulate the anode electrically from the can, the disc 11 could be electrically connected inside the valve to the pin *d*, and thin sheets of mica 39 and 40 could be interposed between the disc and the clamping rings or plates. This would provide the desired electrical insulation while still giving good thermal transfer from the disc to the can.

As explained in the co-pending specification referred to above, it is particularly advantageous to assemble the getter holder 25 in the upper compartment of the valve since it will be well screened from the cathodes by the disc, and there will accordingly be no danger of contaminating the cathodes with the getter material. However, if desired the getter could be suitably arranged in the lower part of the cup 13, and if the disc 11 be composed of a metal (such as one of the cobalt-nickel-iron alloys) which is suitable for sealing to glass on one side only, the dome 12 could be omitted altogether, so that the disc 11 would then form the closing means for the envelope.

Alternatively, the cathodes could be placed on opposite sides of the disc 11, in which case the dome 12 would be replaced by a cup similar to 13 carrying a terminal disc, the getter holder being disposed appropriately in one of the cups. Furthermore, it is obvious that more than two cathodes, insulated from one another, and all sharing in common the anode disc 11, could be arranged on one or both sides of the disc by simple exten-

sion of the arrangements which have been described for the case when there are only two cathodes.

Although for the reasons given the form of the valve with the anode disc sealed to the envelope is preferred, it need not be constructed in this way so long as a common anode is provided for all the separate cathodes. By the term "common anode" is meant either an integral unit or single electrode shared by all the cathodes, or a number of anodes which may be structurally separate, but which are electrically bonded together by suitable wires or conductors so that all are necessarily at the same potential.

While the valve envelope will generally be of glass, the same methods of construction could be applied to quartz and other like materials workable after softening or melting by heat. Such materials will for convenience be called "fusible materials."

What is claimed is:

1. A thermionic valve rectifier comprising an envelope enclosing a plurality of electron emissive cathodes insulated from one another, a plurality of corresponding anodes, and connecting means coupled with said anodes within said envelope to connect said anodes together directly at the same potential.

2. A thermionic valve rectifier comprising an envelope of fusible material, a metallic anode sealed through the said envelope, and a plurality of electron emissive cathodes insulated from one another enclosed in the said envelope, all of the said cathodes being disposed adjacent to corresponding portions of said anode to supply electrons to the said anode when they are appropriately heated and polarised.

3. A thermionic valve rectifier comprising an envelope of fusible material, a metal anode disc sealed through the said envelope dividing it into two compartments, a plurality of electron emissive cathodes enclosed by one of the said compartments and disposed adjacent to corresponding portions of said disc to contribute electrons to the said anode disc when they are appropriately heated and polarised, and a getter holder enclosed in the other compartment.

4. A rectifier according to claim 2 further comprising screen means positioned between adjacent cathodes for preventing the transfer of electrons from one cathode to another.

5. A rectifier according to claim 2 further comprising a metal screen interposed between adjacent cathodes mounted on and electrically connected to the said anode.

6. A rectifier according to claim 3 comprising two cathodes both enclosed in one of the said compartments.

7. A rectifier according to claim 2 further comprising a metal can enclosing the valve, and means for attaching the said anode disc to the can in good thermal contact therewith.

8. A rectifier according to claim 2 further comprising a metal can enclosing said valve, insulation means interposed between said can and said disc cooperating with said can and said disc for attaching said can to said disc.

9. A rectifier according to claim 2 further comprising a metal can having cooling fins and enclosing said valve, and means cooperating with said can and said disc for attaching said can to said disc.

10. A thermionic valve rectifier comprising an envelope of fusible material, a metal anode disc sealed through the said envelope dividing it into

two compartments, a plurality of electron emissive cathodes enclosed in one of said compartments, all of said cathodes being disposed adjacent to corresponding portions of said disc to supply electrons to the said anode when they are appropriately heated and polarized.

11. A thermionic valve rectifier comprising an envelope of fusible material, a metallic anode sealed through said envelope, a plurality of electron emissive cathodes insulated from one another enclosed in said envelope, all of said cathodes being disposed adjacent to corresponding portions of said anode to supply electrons to said anode when they are appropriately heated and polarized, and cooling means external to said envelope and thermally coupled to said anode.
